UNITED STATES PATENT OFFICE.

ARTHUR P. RICARD, OF TOLEDO, OHIO.

MACHINE FOR RIVETING IRON CARRIAGE-WHEELS.

SPECIFICATION forming part of Letters Patent No. 374,998, dated December 20, 1887.

Application filed October 29, 1887. Serial No. 253,755. (No model.)

To all whom it may concern:

Be it known that I, ARTHUR P. RICARD, a citizen of the United States, residing at Toledo, in the county of Lucas and State of Ohio, have 5 invented certain new and useful Improvements in an Automatic Device for Riveting Metal Spokes in Wheel-Rims; and I do hereby declare that the following is a full, clear, and exact description of the invention, which will enable others skilled in the art to which it app- 10 pertains to make and use the same, reference being had to the accompanying drawings, and to the letters of reference marked thereon, which form part of this specification.

15 My invention relates to an automatic device for riveting metal spokes in wheel-rims, and has for its object to automatically present a spoke to be riveted in a position to be held firmly by a gripping device in such relation 20 that an automatically - operated riveter shall rivet the same to the rim of the wheel and then be withdrawn to permit the wheel to make a sufficient turn to present the next spoke to be riveted.

25 Another object is to provide a chuck or wheel-holder, into which the wheel to be completed shall be secured in such a manner as to insure a true circle to the periphery.

A still further object is to provide a clamp 30 for each spoke, that shall have a lateral movement to compensate for any irregularity of the same in the radial position from the hub.

The invention consists in the parts and combination of parts, as will be more fully de- 35 scribed, and pointed out in the claims.

In the drawings, Figure 1 is a plan view of a chuck or wheel-holder and a portion of a table upon which the same is movably mounted. Fig. 2 is a cross-sectional elevation through 40 the center of Fig. 1, and also showing in dotted lines a portion of a wheel secured thereon. Fig. 3 is a detail view of a spoke-clamp. Fig. 4 is a side view of the table, and showing in dotted lines the power-shaft and its connection with the mechanism. Fig. 5 is a top view 45 showing the gripping device in engagement with the spoke-clamp, and also showing the riveter and toggle-arms.

Like letters of reference indicate like parts 50 throughout the several views.

A designates the chuck or wheel - holder composed of a series of threaded rods, D, jour-

naled in a central hub, A', and a rim, E. The number of rods D vary to suit the number of spokes of the wheel to be riveted. Each rod 55 has upon its inner end a bevel-gear, and has a squared outer end, E'. The screw - threads upon the rods are alternately right and left hand, for a purpose hereinafter stated.

F are spoke-clamps, the body of each having 60 a screw-threaded perforation through which a rod, D, passes.

F' are clamping jaws hinged to the body part at F''' and held in close relation to each other by springs F''. 65

G are dies inserted into the jaws, and adjustably held in place by set-screws G' within the jaws F'.

G'' are semicircular grooves within the dies, 70 into which a spoke is gripped.

C is a rectangular plate to which the wheel-holder is secured by being attached to the hub A'. This plate rests upon and slides in ways formed upon the table B.

J, Fig. 4, is a revoluble power-shaft, having 75 cams K and K' and an eccentric, Q, secured thereon. The cam K is connected by means of a yoke, L, and pitman L' with toggle-arms M' and M'', the toggle-arm M' being pivoted at M to the table B and the toggle-arm M' being 80 pivotally attached to a plunger, M''', which abuts against a sliding frame, N, moving in ways upon table B. Cam K' engages with a shoulder on yoke L, for the purpose of raising the same quickly when cam K has depressed 85 the same and passes from engagement therewith. The cams are placed upon the shaft in such relation that their greatest lengths are at right angles to each other.

To frame N are attached arms N', which are 90 pivotally attached to grapple-arms N'', having each a square shoulder, N''', at one end, for a purpose hereinafter stated. Arms N'' are fulcrumed at O' upon a cross-bar, O, attached to table B.

N'' are coiled springs attached to frame N and to a fixed part of the table. 95

Eccentric Q is connected by means of yoke R and pitman R' with toggle-arms S' and S'', arms S' being pivotally attached to table B at 100 S and arm S'' being pivotally attached to a reciprocating plunger, T, having a riveting-head, T'.

Upon the outer end of shaft J is formed a

cam-shaped lug, J', adapted to actuate a bell-crank lever, X, pivoted to the table at Y.

U designates a rod attached at one end to an arm of the bell-crank lever, and at the opposite end to a spring, W, attached to table B by being secured to a depending lug, Z. The inner end, U', of rod U is screw-threaded and passes through a perforation in a lug, V, formed upon the bottom of plate C, and is held to any desired adjustment by means of nuts V'.

P is a catch pivoted in standards upon frame N, and adapted to engage with a lug upon plunger M'', to hold frame N in its advanced position when the grapple-arms are in engagement with the spoke-clamp.

P'' is a frame connected to the table and extending across the ways into which plunger M'' moves, and in a position to trip the catch.

H designates a short stud screwed into hub A' of the chuck or wheel-holder, onto which the hub of a wheel to be finished is placed, the spokes H' radiating therefrom to the spoke-clamps, and are firmly grasped by the same in such manner that the end H'' of the spoke, or so much thereof as is to be riveted, protrudes at the opposite side of the dies in the clamps, as shown in Figs. 2 and 4.

The hub A' of the wheel-holder is provided with ratchets I, corresponding in number with the number of spoke-clamps.

I' is a spring-pawl attached to the table and engaging with the ratchets.

In operation the wheel is placed upon wheel-holder A, the stud H passing through the hub thereof, the lower section of spokes—that is, the spokes comprising one side of the wheel, (there being eight on each side in a sixteen-spoke wheel)—are placed within the dies in the spoke-clamps. The operator now causes the clamps F to move toward the rim of the wheel. This is done by revolving any one of the threaded rods D by means of a crank fitting upon the squared ends E' of the rod. It will be seen that as each alternate rod has a left-hand screw-thread the action of the bevel-gears is to so revolve the rods that all of the clamps F will approach or recede from the periphery of the wheel in unison, thereby tending to give the rim of the wheel a true circle, and also to insure an even length to the spokes. Upon shaft J being revolved lug J' depresses the free arm of bell-crank lever X, causing rod U to move plate C, and, as a consequence, wheel-holder A, toward the riveter. This movement of plate C causes pawl I' to engage with a ratchet, I, upon hub A', and gives the wheel-holder a one-eighth turn, thereby presenting a spoke directly in front of the riveter. Upon shaft J continuing its revolution, cam K forces yoke L and pitman L' downward, causing arms M' and M'' to straighten, thereby, through the medium of plunger M'', moving frame N and causing grapples N'' to grasp the clamps F and hold the same firmly to place. At this time catch P engages with lug P'' and holds the frame N from back movement. Eccentric Q has at this

time been revolved to bring its greatest point of eccentricity to bear upon the lower portion of yoke R, thereby depressing the same and straightening toggle-arms S' S'', causing the riveter to approach and rivet the end H'' of the spoke, whereupon cam K passes from engagement with yoke L, permitting cam K' to quickly raise the yoke, thereby shortening the toggle and withdrawing plunger M'', at which time frame N is moved back (by the connection of catch P with plunger M'') a sufficient distance to open the grapples, permitting the wheel-holder to move forward, as will presently appear. The catch P is now tripped by the free end of the same passing beneath frame P'', permitting springs T'' to move frame N forward, closing the grapples to a certain extent, ready to be opened by and be engaged with the spoke-clamp as it is pressed between the same as the wheel-holder advances. Simultaneously with this movement lug J' passes off of the arm of bell-crank lever X, and spring W moves the wheel-holder back a sufficient distance to permit it to turn upon plate C. Cam Q raises yoke R and, through its connection with the toggle S' S'', withdraws plunger T and riveter T' in position to again advance, when the operation just described is repeated.

It will be seen that at one revolution of the shaft the whole operation of turning the wheel-holder, riveting a spoke, and separating the parts is accomplished.

While I have shown dies in the spoke-clamps adapted for a single spoke, I may arrange the same to clamp two spokes at the same time.

It will be understood that the number of rods and spoke-clamps may be varied to suit the character of the wheel to be operated upon. It will also be seen that the rods may all be formed with a right-hand thread, and be given the proper direction of revolution by idlers, or in any other preferred manner.

Having described my invention, what I claim, and desire to secure by Letters Patent, is—

1. In a riveting-machine, a chuck or wheel-holder having spoke-clamps movable radially from the center, as and for the purpose set forth.

2. In a riveting-machine, a chuck or wheel-holder having threaded rods, and spoke-clamps upon the rods adapted to be moved radially by the revolution of the rods, as and for the purpose set forth.

3. A chuck or wheel-holder comprising rods threaded alternately right and left, each rod having a bevel-gear upon its inner end and a squared outer end, and spoke-clamps mounted upon the rods in such manner as to move radially from the center of the chuck by the revolution of the rods, as and for the purpose set forth.

4. In a chuck or wheel-holder, spoke-clamps having hinged jaws held closed by yielding connections, as and for the purpose set forth.

5. In a wheel-holder, spoke-clamps having jaws adapted to be opened and closed for the

insertion or removal of spokes, each jaw having a die for clamping the spoke, as and for the purpose set forth.

6. In a device for riveting metal spokes in wheel-rims, a power-shaft provided with a lug, and a bell-crank lever one end of which is in the path of the rotation of said lug, the opposite end being connected to a movable table having a wheel-holder mounted thereon, as and for the purpose set forth.

7. In a device for riveting metal spokes in wheel-rims, in combination with a spoke-clamp, grapples connected with movable arms, said arms being reciprocated by means of a cam upon the power-shaft, as and for the purpose set forth.

8. In a device for riveting spokes in wheel-rims, grapple-arms opened from and closing into engagement with a spoke-clamp by the reciprocation of a frame to which the grapples are attached, as and for the purpose set forth.

9. In a device for riveting spokes in wheel-rims in which grapples are opened and closed by the action of arms in connection with the power-shaft, a catch attached to a frame and adapted to engage with a lug on the plunger, and springs connected with the table and frame, as and for the purpose set forth.

10. In a device for riveting spokes in wheel-rims, in combination with a spoke-clamp, a riveter connected with arms operated by an eccentric upon the power-shaft, as and for the purpose set forth.

In testimony that I claim the foregoing as my own I hereby affix my signature in presence of two witnesses.

ARTHUR P. RICARD.
